UNITED STATES PATENT OFFICE.

CHARLES E. THOMPSON, OF DENVER, COLORADO, ASSIGNOR TO THE MINE & SMELTER SUPPLY COMPANY, OF DENVER, COLORADO, A CORPORATION OF COLORADO.

TABLE FOR ORE AND COAL WASHING.

1,180,209.

Specification of Letters Patent.

Patented Apr. 18, 1916.

Application filed May 31, 1913. Serial No. 771,008.

To all whom it may concern:

Be it known that I, CHARLES E. THOMPSON, a citizen of the United States, residing at the city and county of Denver and State 5 of Colorado, have invented certain new and useful Improvements in Tables for Ore and Coal Washing, of which the following is a specification.

My invention relates to an improvement 10 in transversely inclined reciprocating concentrating or washing tables for washing coal, it being a table the surface of which changes diagonally thereacross along two or more lines suitably spaced, whereby the 15 surface of the table is subdivided into a plurality of fields or areas of varying formations, whereby a table is provided of superior efficiency, capacity and effectiveness in washing, cleaning and separating the material to be treated.

With these objects in view, my invention 20 comprises a table, the surface of which is characterized by a plurality of areas or planes rifled throughout, but the height of 25 which rifles varies over certain areas and is uniform over others, the lines separating these fields or areas extending diagonally across the surface of the table, and intersecting the rifles at points where the latter 30 are of uniform height.

My invention further consists of means of flexing the table along one or more of these diagonal lines.

In the accompanying drawings:—Figure 35 1 is a plan view, Figs. 2, 3, 4 and 4^a are longitudinal sectional views taken at different points throughout the length of the table to show the relative height and taper of the rifles at different areas, Figs. 5, 6, 7 and 8 40 are transverse sections, and Fig. 9 is a plan view of the table frame with the riffle surface removed to show the frame-work construction.

The surface of the table 1 is preferably 45 rifled throughout, and in the form of the table illustrated—which is one of many possible exemplifications of my invention—the rifles at the feed or head end start at the feed-box 2 at the upper right-hand corner, 50 preferably at a height of seven-sixteenths ($\frac{7}{16}$) of an inch, gradually increasing in height across the head end of the table to five-eighths ($\frac{5}{8}$) inch in height at the lower discharge side; and from this head end the 55 rifles gradually taper more or less abruptly

in the neighborhood of the feed-box, and much more gradually at the lower discharge side, so that from the upper to the lower side these rifles reach a uniform height along an advancing or diagonal line as indicated by 60 the dotted lines 6—6, where they are all preferably three-eighths ($\frac{3}{8}$) of an inch high, thus forming a field or area E at the head end of the table more or less triangular. From this diagonal or advancing 65 line 6—6 of uniform height in the rifles, the rifles continue at uniform height, those at the upper side of greater length and gradually decreasing toward the lower discharge side of the table until they reach a diagonal 70 line indicated by the dotted line 7—7 of advancing terminals forming a field or area B, over which all portions of rifles of varying length are of uniform height. From the line 7—7 the rifles taper preferably from a 75 uniform height of three-eighths ($\frac{3}{8}$) of an inch diagonally across the table to a uniform height of one-eighth ($\frac{1}{8}$) of an inch at the advancing line of change in elevation indicated by the dotted lines 8—8, forming the 80 field or area C, and from this line 8—8 to the discharge end of the table the rifles are again of uniform height forming the area D of relatively shallow rifles.

The head-motion (not shown) is as usual 85 at the feed end of the table, imparting a reciprocating motion lengthwise of the latter. The table is transversely inclined, having a side wash of water transversely across the rifles and the fields or areas E, B, C and D, 90 and the heavier material discharges at the end opposite from the head-motion, and the lighter across the lower discharge side.

It may be desirable to flex the table along the lines 6—6, 7—7, 8—8 between the several fields or areas as shown in Fig. 9, any 95 approved means being used for effecting this flexing, which it may be stated may be found desirable along only one or more of these dividing lines.

A table of this construction is more particularly adapted for washing culm or finely broken coal for the removal of bone or slate or incombustible material therefrom, and the bone or ash being of the greater specific 100 gravity passes over the end of the machine while the coal to be saved in two or more grades is discharged over the major portion of the discharge side or edge of the table.

While I have described with some par. 110

ticularity the preferred relative height and proportions, I do not by any means wish to be confined to these dimensions, as these relations and proportions, while desirable for the greatest efficiency so far as experiments already made and the results analyzed have proven, nevertheless, with larger sizes of material to be treated, of course the height of riffles may be advantageously increased; 10 and with the finest of culms worth saving the same might likewise be decreased while maintaining the same general relativity which seems desirable.

15 The effect of tapering or gradually reducing the height of riffles is well known in the art of concentration in the type to which this table belongs, for, with the gradual shallowing of the grooves, more and more of the material is exposed to the side flow or wash of water, so that the lighter is being poured off and carried down the slope of the table for re-treatment. This operation continually repeats itself on the table surface, whereas the channels of uniform depth 20 in the alternate areas serve more or less as conveyers to conduct the material to the next area in which the riffles gradually diminish in height.

30 Having fully described my invention, what I claim as new and desire to secure by Letters Patent, is:—

35 1. A table for ore and coal washing, the entire surface of which is riffled from one end of the table to the other, forming alternate areas across the table in which the riffles are uniform and tapering, one of these areas having the tapering riffle located at the feed end and one area in which the riffles are of uniform height located at the 40 opposite or concentrates discharge end, the mergers between uniform and tapering

riffles forming diagonal lines across the table.

2. A table for ore and coal washing, the entire surface of which is riffled from one 45 end of the table to the other, forming alternate areas across the table in which the riffles are uniform and tapering, one of these areas having the tapering riffle located at the feed end and one area in which the riffles are of uniform height located at the opposite 50 or concentrates discharge end, the mergers between uniform and tapering riffles forming diagonal and non-parallel lines across the table. 55

3. A table for ore and coal washing, the entire surface of which is riffled, said riffled surface divided into a plurality of different areas, the boundaries or dividing lines between which are diagonal and non-parallel, 60 the riffles in alternate areas diminishing in height, and in the remaining areas of uniform height.

4. A table for ore and coal washing, the entire surface of which is riffled, said riffled surface divided into a plurality of different areas, the boundaries or dividing lines between which are non-parallel, the riffles in alternate areas diminishing in height, and in the remaining areas of uniform height, 65 the riffles in the areas in which the height of riffle is uniform corresponding in height throughout their length with the lowest point of the tapered riffles, toward the head-motion end of the table, of which they are 70 continuations. 75

In testimony whereof I affix my signature, in the presence of two witnesses.

CHARLES E. THOMPSON.
